HYDRAULIC PUMP OR MOTOR

James Robinson, Detroit, Mich., assignor to
Vickers Incorporated, Detroit, Mich., a corpora-
tion of Michigan

Application June 28, 1939, Serial No. 281,645

6 Claims. (Cl. 103—162)

This invention relates to power transmissions and more particularly to those of the type comprising two or more fluid pressure energy translating devices, one of which may function as a pump and another as a fluid motor. In such devices of the type which comprise a revolving cylinder barrel having a plurality of parallel cylinder bores therein within which pistons are reciprocated by a swash plate device, it is customary to provide a rotary valving mechanism which is operated by the rotation of the cylinder barrel itself for the purpose of alternately connecting each cylinder bore with the inlet and outlet passages of the device. Many machines of this character utilize a plate type valve formed by a flat surface of the cylinder barrel which runs in abutting and in fluid sealing relationship on a stationary flat valve plate. The plate type valve may be so constructed that the cylinder barrel is constantly pressed into engagement with the valve plate by hydraulic pressure so that the clearance at the valve is automatically adjusted to take care of variations in oil viscosity and to compensate for wear. This is a distinct advantage and contributes much to the reliability and long life of machines employing a valve of this character.

It is customary with machines of this character to so proportion the size of the distributing ports in the end face of the cylinder barrel relative to the piston area and to the area of the annular surface of contact with the valve plate as to closely approach hydraulic balance between the fluid pressure forces exerted by piston reaction on the end faces of the cylinder bores and the fluid pressure separating forces exerted in the oil film between the cylinder barrel and valve plate. It is, of course, impossible in practice to provide an exact balance between these forces, and since it is necessary to provide some means for holding the barrel in contact with the valve plate while the machine is idle, a spring or other resilient means is usually provided for urging the barrel into contact with the valve plate with a relatively light force at all times.

It is extremely difficult to predetermine with precision the exact amount of hydraulic unbalance which will exist in a given machine since small variations in dimensions which are entirely within normal manufacturing tolerances produce large changes in the hydraulic balance when the operating pressures are high. Thus, in order to insure that, in spite of tolerance variations, all machines will have a positive unbalance in the same direction, it would be necessary

to design them with a substantial amount of unbalance sufficient to allow for the largest tolerance variation normally encountered without causing the direction of unbalance to change. If the net unbalance is in a direction holding the barrel in contact and is very large, then the unit bearing pressures at the valve plate are apt to be excessive. On the other hand, if the machine is designed for a very small net unbalance tending to hold the barrel in contact it occasionally happens, due to manufacturing variations, that the net unbalance of the hydraulic forces on the barrel becomes reversed and is in a direction tending to lift the barrel off from the valve plate, and in such cases the spring is sufficient to maintain the barrel in contact with the valve plate at all operating pressures below a certain maximum. When this maximum is exceeded, however, the barrel lifts away from the valve plate, and since the valve is thereby rendered ineffective, the power drive through the transmission is completely and suddenly interrupted. This difficulty can be extremely troublesome at times, particularly where the transmission is used to operate a device, such as a hoist, which has to overcome a gravity load and in which complete dependence upon the transmission is placed for sustaining that load. In such cases it occasionally happens that the critical pressure at which the barrel will blow off is slightly above the normal operating pressure required for lifting the usual loads and that on rare occasions, due to snagging of hoisting lines or some other momentary small overload during hoisting, the critical pressure is exceeded causing the barrel to lift and resulting in dropping of the load with consequent damage thereto.

It is an object of the present invention to provide a valve plate construction for a fluid pressure energy translating device of the class described in which the above problems are avoided by the provision of means for exerting a variable force on the cylinder barrel such that the total force tending to hold the barrel on the valve plate is not proportional to operating pressure variations and preferably substantially constant. It thereby becomes possible to design the machine with a substantial degree of unbalance tending to hold the barrel in contact at low pressures and at the same time avoid increasing the total force holding it in contact as the operating pressure increases. At the same time all necessity is avoided of trying to approach true hydraulic balance so closely as to admit of occasional reverses in unbalance in machines hap-

pening to come at the limit of manufacturing tolerance.

Further objects and advantages of the present invention will be apparent from the following description, reference being had to the accompanying drawing wherein a preferred form of the present invention is clearly shown.

In the drawing:

The single figure is a longitudinal cross section of a fluid pressure energy translating device incorporating a preferred form of the present invention.

The embodiment of the invention selected for illustration comprises a pump of the same general class as that illustrated in the patent to Hans Thoma, No. 1,931,969, and comprises generally a main ring-like frame member 10 having a mounting flange 12 thereon and provided with bearings 14 on which a main shaft 16 is journaled. The shaft 16 is provided with a 15 socket flange 18 carrying a plurality of ball sockets 20 in which are mounted ball-ended connecting rods 22 carrying reciprocating pistons 24.

Rigidly secured to the frame member 10 by suitable bolts not shown are a pair of plates 26 provided with bearings 28 and with fluid connections 30. Journalled on the bearings 28 is a swinging yoke generally designated as 32 comprising a valve plate 34 with rigidly attached hollow arms 36 providing trunnions for the yoke and connected to the fluid connection 30 by sealing sleeves 38.

The valve plate 34 is provided with an arcuate raised sealing surface 40 against which runs the flat end face 42 of a cylinder barrel 44 provided with a plurality of cylinder bores 46 therein. Formed in the valve plate 34 are two arcuate fluid distributing ports 48 each of which extends through an arc somewhat less than 180 degrees and communicates with the passages in the hollow arms 36. Formed at the left-hand end of the cylinder bores 46 are a plurality of fluid distributing ports 50 opening into the flat face 42 and adapted to alternately register with each of the distributing ports 48. A shaft 52 provided with universal joints 54 at its opposite ends connects the barrel 44 to rotate with the shaft 16 in any position of the yoke 32. The parts thus far described are in a broad aspect well known in the art and per se form no part of the present invention.

The hydraulic balance of the cylinder barrel 44 is, of course, determined by suitable proportioning of the radial width of the flat pressure surface 40 relative to the total area of all of the ports 50 and the total area of all of the pistons 24. With the present invention these areas are so proportioned as to produce a net fluid pressure force on the cylinder barrel 44 tending to urge the barrel into contact with the surface 40. This unbalance is made as small as possible, however, and is, of course, proportional to the operating pressure.

According to the invention, means is provided for imposing an additional force tending to urge the barrel into contact with the surface 40 which comprises a spring 56, the left-hand end of which abuts the inner race of a ball bearing 58 the outer race of which rests against a shoulder formed at the left-hand end of a recess 60 formed in the barrel 44. The right-hand end of the spring 56 is positioned by a spring abutment 62 rigidly secured to the end of a rod 64 mounted in a bore 66 in the valve plate 34.

Also formed in the valve plate 34 is a cylindri-

cal chamber 68 in which is slidably mounted a piston 70 integrally formed on the rod 64. The left-hand end of the rod 64 carries an adjustable spring abutment 72. A spring 74 is interposed between the abutment 72 and a spring cup 76 rigidly secured to the left-hand end of the valve plate 34. A suitable cap 78 may be mounted on top of the valve plate 34. A suitable cap 78 may be mounted on top of the spring cup 76. The left-hand end of the chamber 68 is in communication with one of the valve plate ports 48 through a drilled passage 80. The single passage 80 is suitable for use with pumps or motors of the type where the high operating pressure is always at one port of the machine and is never reversed. For devices where the high pressure side may be at one or the other of the ports 48 depending on operating conditions, the passage 80 may lead to both ports 48 with the provision of a shuttle valve operating in the well-known manner to connect the chamber 68 with whichever port happens to be the high pressure port at any instant. A passage 82 is provided for draining the right-hand end of chamber 68.

In operation, assuming that the conduits 30 are connected into a power transmission circuit in the usual manner so that the upper conduit 30 is the pressure supply connection while the lower one is the suction connection and that the shaft 16 is connected to a suitable prime mover and rotated thereby at a constant speed, with the top moving away from the observer the pistons 24 are reciprocated in the cylinder bores 46 in the well-known manner with a stroke depending upon the angular displacement of the yoke 32.

With the left-hand end of the yoke moved away from the observer each piston 24 will travel to the left during its top-half revolution and will be withdrawn to the right during its bottom-half revolution, thus withdrawing fluid from the lower port 48 into the cylinder 46 and discharging it out of them into the upper port 48.

At zero operating pressure in the upper port 48 the pressure in chamber 68 is likewise zero and the two springs 74 and 56 balance one another so that each exerts an equal force. The force of spring 56 is transmitted through the bearing 58 to the cylinder barrel 44 and is the sole force urging the barrel into contact with the valve plate. As the pressure in the upper port 48 increases this pressure is transmitted to the chamber 68 and moves the piston 70 to the right by an amount proportional to the increase in pressure, thus increasing the tension on the spring 74 and decreasing the tension on the spring 56. Accordingly the force which the spring 56 exerts on the cylinder barrel 44 is decreased in proportion to increases in pressure in the upper port 48.

The force which the hydraulic fluid in the cylinders 46 exerts on the cylinder barrel, that is, the net hydraulic unbalance of the barrel, increases in direct proportion to the pressure in port 48 so that accordingly the total force exerted on the cylinder barrel 44 remains substantially constant. Obviously the designed proportions of the device may be varied in such a manner as to provide either exactly constant force on the barrel 44 or to provide increasing pressure or vice versa depending upon the balance of design factors such as the rate of spring 56, the area of the piston 70, and the net hydraulic unbalance of the barrel 44.

While the form of embodiment of the invention as herein disclosed constitutes a preferred

form, it is to be understood that other forms might be adopted, all coming within the scope of the claims which follow.

What is claimed is as follows:

1. In a fluid pressure energy translating device having a plurality of cylinders and pistons reciprocable therein, a rotary valve structure comprising two relatively rotatable members provided with flat, annular, sealing surfaces in running engagement and containing fluid distributing ports communicating with said cylinders, one of said members having an area exposed to fluid pressure from said cylinders tending to urge said member into abutment with force proportional to said pressure, resilient means also tending to urge said members into abutment, and pressure responsive means including a spring-biased fluid motor acting through said resilient means on said member for varying the force of said resilient means in inverse proportion to said pressure.

2. In a fluid pressure energy translating device having a plurality of cylinders and pistons reciprocable therein, a rotary valve structure comprising two relatively rotatable members provided with flat, annular, sealing surfaces in running engagement and containing fluid distributing ports communicating with said cylinders, said members being hydraulically balanced against at least a major portion of the separating force normally existing between said surfaces, an expansible chamber in communication with one of said ports and having a spring-biased movable member, and means forming a resilient connection between said movable member and one of said rotatable members through which said movable member acts on the rotatable member.

3. In a fluid pressure energy translating device of the type having a revolving cylinder barrel with a plurality of cylinders therein and pistons reciprocable in the cylinders, a rotary valve structure comprising a stationary valve having a flat annular surface with fluid distributing ports therein, means forming a flat annular surface on the cylinder barrel adapted to abut the valve plate surface and provided with fluid distributing ports therein, said barrel being provided with fluid pressure areas exposed to the pressure in said cylinders for exerting a force on the barrel proportional to such pressure tending to urge the barrel into abutment with valve plate, resilient means for also urging the barrel into abutment with the valve plate, and pressure responsive means including a spring-biased fluid motor acting through said resilient means on said mem-

ber for varying the force of said resilient means in inverse proportion to said pressure.

4. In a fluid pressure energy translating device of the type having a revolving cylinder barrel with a plurality of cylinders therein and pistons reciprocable in the cylinders, a rotary valve structure comprising a stationary valve having a flat annular surface with fluid distributing ports therein, means forming a flat annular surface on the cylinder barrel adapted to abut the valve plate surface and provided with fluid distributing ports therein, said barrel being hydraulically balanced against at least a major portion of the separating force normally existing between said surfaces, an expansible chamber in communication with one of said ports and having a spring-biased movable member, and means forming a resilient connection between said movable member and the cylinder barrel through which said movable member acts on the rotatable member.

5. In a fluid pressure energy translating device having a plurality of cylinders and pistons reciprocable therein, a rotary valve structure comprising two relatively rotatable members provided with flat, annular, sealing surfaces in running engagement and containing fluid distributing ports communicating with said cylinders, said members being subject to a net hydraulic force tending to hold the members against separation, resilient means for applying additional force holding the members against separation, and means including a spring-biased fluid motor acting through said resilient means on said member for decreasing the force of the resilient means with increases in operating pressure of the device.

6. In a fluid pressure energy translating device of the type having a revolving cylinder barrel with a plurality of cylinders therein and pistons reciprocable in the cylinders, a rotary valve structure comprising a stationary valve having a flat annular surface with fluid distributing ports therein, means forming a flat annular surface on the cylinder barrel adapted to abut the valve plate surface and provided with fluid distributing ports therein, said barrel being subject to a net hydraulic force tending to hold the barrel against the valve plate, resilient means for applying additional force in the same direction, and means including a spring-biased fluid motor acting through said resilient means on said member for decreasing the force of the resilient means with increases in operating pressure of the device.

JAMES ROBINSON.
